RIVETING MACHINE FOR MATTRESS
BORDERS

Sam Marsack, Milwaukee, and William Loeffler, Jr., Sheboygan, Wis., assignors, by mesne assignments, to Marsack Patents Corporation, Milwaukee, Wis., a corporation of Delaware

Application November 5, 1936, Serial No. 109,284

14 Claims. (Cl. 218—0.5)

This invention relates to riveting machines and particularly to a machine for securing together the strips of material comprising mattress borders used in the manufacture of mattresses.

5 One object of the present invention is to provide a machine which will feed the several materials comprising a mattress border through the machine intermittently in proper relation and, at suitable intervals, secure the materials together by transverse rows of rivets.

Another object of the invention is to provide novel means for holding and driving the rivets through the materials of the border during the intervals between the movements of the materials 10 through the machine.

Another object of the invention is to provide novel means for automatically feeding rivets singly to said rivet holding and driving means and in proper position to be engaged by the 20 driving means for projecting rivets through the materials of the border to secure the materials together.

Another object of the invention is to provide means for automatically actuating the rivet feeding and driving means in properly timed relation 25 for supplying rivets to the driving means to be engaged thereby and inserted through the materials of the border during the intervals between the intermittent movements thereof.

30 A further object of the invention is to provide novel means for insuring positive delivery of rivets from the feeding means to the rivet driving means.

A still further object of the invention is to improve machines of the character described in 35 sundry details hereinafter referred to and particularly pointed out in the appended claims.

One embodiment of the present invention is shown for illustrative purposes in the accompanying drawings, in which:

Fig. 1 is a front elevational view of a mattress border riveting machine embodying features of the present invention;

45 Fig. 2 is a rear view of the machine illustrated in Fig. 1;

Fig. 3 is an enlarged sectional elevational view taken substantially as indicated by the lines 3—3 of Figs. 1 and 2;

50 Fig. 4 is a side elevational view on a reduced scale of the machine illustrated in Figs. 1 and 2, and taken as viewed from the right and left sides thereof, respectively;

Fig. 5 is an enlarged sectional plan view taken 55 substantially as indicated by the line 5—5 of Fig.

2, illustrating a portion of the rivet feeding means;

Fig. 6 is a further enlarged plan view of one of the rivet feeding units illustrated in Figs. 3 and 5, and taken substantially as indicated by the 5 lines 6—6 of Figs. 3 and 7;

Fig. 7 is a sectional elevational view through the rivet feeding unit shown in Fig. 6, and illustrating its relation to our novel rivet holding and driving means, the portion of Fig. 7 illustrating 10 the feeding means being taken substantially as indicated by the line 7—7 of Fig. 6;

Fig. 8 is a fragmentary sectional elevational view similar to a portion of Fig. 7 showing various parts of the rivet feeding means in changed position;

Fig. 9 is a front sectional elevational view of a portion of the rivet feeding means taken substantially as indicated by the line 9—9 of Fig. 7;

Fig. 10 is a front sectional elevational view of 20 a portion of the rivet feeding means taken as indicated by the line 10—10 of Fig. 7;

Fig. 11 is a fragmentary elevational view partly in section of a portion of the structure illustrated in Figs. 6, 7, 8, and 10, and taken substantially 25 as indicated by the lines 11—11 of Figs. 6 and 10;

Fig. 12 is a perspective view of a rivet supporting member and gate-cam associated therewith and forming a part of the rivet feeding means;

Fig. 13 is a fragmentary perspective view of 30 the upper end of a rivet chute and stripping finger forming a part of the rivet feeding means;

Fig. 14 is a vertical sectional elevational view through the rivet holding and driving means shown in Figs. 3 and 7, certain of the structure 35 illustrated in Fig. 14 being shown in changed position from that shown in Fig. 7;

Fig. 15 is a front elevational view, partly in section of the structure illustrated in Fig. 14, the sectional portion being taken substantially 40 as indicated by the line 15—15 thereof;

Fig. 16 is a plan sectional view taken substantially as indicated by the line 16—16 of Fig. 14;

Fig. 17 is a fragmentary sectional elevational view of a portion of the mattress border materials 45 secured together by rivets inserted therethrough by a machine embodying features of the present invention; and

Fig. 18 is a perspective view of a preferred type of rivet used in the operation of the machine. 50

As shown in the drawings, the illustrative embodiment of the present invention comprises, in general, a frame, indicated as a whole by the numeral 21, having a main drive shaft 22 rotatably mounted therein and operatively connected 55

Rivet feed

to mattress border feeding means indicated, generally, by the numeral 23 (Figs. 1 and 3) for feeding the mattress border, indicated as a whole by the letter A, through the machine in a manner to be operated upon by rivet driving means indicated, generally, by the numeral 24 having rivet holding means, indicated as a whole by the numeral 25, associated therewith, the rivet holding means 25 and driving means 24 being also operatively connected to the shaft 22 in a manner to be actuated thereby in proper relation to the movements of the mattress border A through the machine.

The shaft 22 is also operatively connected to rivet feeding means, indicated as a whole, by the numeral 26, designed for feeding rivets singly to the respective rivet holding means 25 in position to be engaged by the rivet driving means 24, and in proper relation to the movements thereof.

For driving the machine and the various operating parts associated therewith from a suitable source of power, the main drive shaft 22 is operatively related to a main driving pulley 27 (Figs. 1, 2, 3 and 4) having a belt 28 thereon connected to a suitable source of power, not shown, by which the machine may be operated, the drive shaft 22 being connectable with the pulley 27 by suitable clutch mechanism 29 of a well known type, such, for example, as illustrated and described in United States Letters Patent No. 1,775-534, issued to Max Marsack et al., September 9, 1930, the clutch 29, in the present instance, being controlled by a lever 31 pivotally mounted at 32 (Fig. 4) on the frame 21 and connected to the clutch 29 by a rod 33 adapted normally to be held in raised position by a spring 34 (Fig. 1) for normally disengaging the clutch and permitting free rotation of the driving pulley 27 without transmitting motion to the main drive shaft 22, it being understood that when the rod 33 is drawn downwardly by the lever 31, the clutch 29 will engage to rotate the shaft 22.

Mattress border feed

For feeding the material of the mattress border A consisting of layers of fabric B and C and a filler D between a lower guide 35 (Figs. 3 and 4) and a combined upper guide and presser foot 36, a pair of upper and lower feed rollers 37 and 38, respectively, are mounted on rotatable shafts 39 and 41, respectively, carried by the frame 21, the shafts 39 and 41 being provided, respectively, at one of their outer ends with inter-engaging pinions 42 and 43 (Figs. 1 and 4), the shaft 41 and pinion 43 having a ratchet 44 secured thereto and adapted to be engaged by a pawl 45 (Fig. 4) mounted on an arm 46 carried by a rock shaft 47 positioned in axial alignment with the shaft 41. To the rock shaft 47 is secured an arm 48, 60 to the outer free end of which is connected the lower end of a rod 49, the opposite or upper end of the rod 49 being adjustably connected to an arm 51 carried by the drive shaft 22 in a manner to be rotated therewith when the clutch 29 is in operative engaging position.

It will be observed from the foregoing description that by an arrangement of the character described, the feed rollers 37 and 38 will be intermittently rotated during each revolution of the shaft 22 in a manner to feed the mattress border A through the machine intermittently, or in a step by step movement, the pawl and ratchet connection 45-44 being operative only during the upward swing of the arm 51.

For supplying rivets to the rivet feeding means 26, a plurality of containers 52 (Figs. 2 and 3), four containers being shown in the present instance, are mounted on the frame 21, each of the containers having a rivet magazine 53 associated therewith for directing rivets from the respective containers to each of four rivet feeding devices comprising the feeding means 26. Each of the containers 52 is provided with a rotating brush 54 for agitating the rivets within the container in a manner to discharge and position them in the respective magazines 53, as clearly shown and more fully described in the above mentioned Patent No. 1,775,534, the brushes 54, 15 in the present instance, being driven through a system or train of gearing 55 operatively connected to a shaft 56 having a pulley 57 secured thereto adapted to receive a belt 58 trained over a pulley 59 mounted on the shaft 22 by which the brushes 54 may be rotated during the rotation of the shaft 22.

For feeding the rivets singly or one at a time from adjacent the lower or discharge ends of the respective magazines 53, there are provided a plurality or series of rivet feeding devices slidably mounted on supporting blocks 61 (Figs. 6 and 7) adjustably mounted on rods 62 carried by the frame 21, the blocks 61 being adjustable on the rods 62 for positioning the feeding devices in proper relation to the magazines 53, and may be secured in desired position with respect to the rods 62 by means of set screws 63.

Each of the feeding devices (Figs. 5 to 13, inclusive) of which four are shown in the present instance (Figs. 2 and 5) comprises a rivet supporting member 64 slidably mounted to reciprocate on a block 61, and having bifurcated portions 65 positioned adjacent the lower discharge end of one of the magazines 53 in a manner to receive the rivets therefrom successively and in alignment with respect to each other when the supporting member 64 and associated elements are in the position shown in Fig. 7, the bifurcations 65 forming an elongated slot 66 adjacent the central longitudinal portion of the supporting member 64 for receiving the shank portions of the rivets mounted on the bifurcations 65. For limiting the movement of the rivets along the supporting surface of the bifurcations 65 and to retain them in proper position to be acted upon by the feeding devices, a yieldable pawl, indicated as a whole by the numeral 67, is pivotally mounted at 68 on the block 61, the lower end of the pivoted portion 69 being engaged by a spring 71 (Fig. 11) for normally urging the free end of the pawl into engagement with the rivet supporting upper surface of the bifurcations 65, as clearly illustrated in Figs. 7 and 11.

For separating or segregating the leading rivet from an adjacent rivet of those positioned on the rivet supporting member 64, a gate 72 is mounted on a head 73 having a pair of vertically disposed rods 74 connected thereto and slidably positioned in apertures formed in the block 61, the apertures having enlarged portions or counterbores 75 adapted, respectively, to receive springs 76 operative between the inner ends of the counterbores 75 and washers or nuts 77 secured to the lower end of the rods 74 for normally urging the gate 72 in a downward direction and in a manner to force a pair of spaced fingers 78 (Fig. 9) on the lower edge of the gate between the head of a leading rivet and an adja-

cent rivet head positioned on the supporting member 64, and to prevent wedging or jamming of the leading rivet head between the fingers 78 and the pawl 67 when the gate 72 is moved downwardly by the springs 76, the pawl 67 is provided adjacent its free end with an inclined cam surface 79 by which the free end of the pawl may be lifted slightly against the action of the spring 71 to prevent any such wedging action.

10 For raising the gate 72 to permit the rivets from the magazine to pass beneath the gate and into the position illustrated in Fig. 7, the rivet supporting member 64 is provided with a pair of gate operating cams, indicated as a whole by the numeral 81, secured to the member 64 by means of screws 81a, each of the cams having a high portion 82 engageable with the gate for supporting the gate in raised position, and having a low portion 83 for permitting the gate to be lowered by the action of the springs 72, thereby projecting the fingers 78 between adjacent rivets on the supporting member 64, when the member 64 is moved to the left from the position shown in Fig. 7, or toward the position shown in Fig. 8, the higher and lower cam portions or surfaces 82 and 83 being connected by an inclined portion 84 to permit easy movement of the gate 72 from one surface to the other.

For removing the leading rivet segregated by the fingers 78 of the gate 72 from its position on the upper edges of the bifurcations 65 when the supporting member 64 is moved to the left from the position shown in Fig. 7, or toward the position shown in Fig. 8, the inner or adjacent faces of the bifurcations 65 are provided with preferably inclined downwardly extending grooves 85 and also with recesses 86 (Figs. 6 and 12) adjacent the upper ends of the grooves 85 to permit the head of the leading rivet to drop into the grooves 85 when the rivet supporting member 64 is moved to the position shown in Fig. 8, at which time a pair of cam members 87 mounted on the bifurcations 65 will have been brought into engagement with a portion 88 of the pawl 67 in a manner to raise the free end of the pawl, as clearly illustrated in Fig. 8, thereby completely freeing the head of the leading rivet from any binding action between the gate 72 and cam portion 79 of the pawl, and leaving the rivet head free to drop through the space adjacent the recesses 86 into the grooves 85 in a manner to rest on guide flanges 89 formed by the lower sides or margins of the grooves 85. Thereafter, upon movement of the rivet supporting member 64 to the right from the position shown in Fig. 8, the head of the rivet on the guide 89 will be engaged by a stripping finger 91 extending into the slot 88 and forced along the guides 89 to a position where the rivet may enter an inclined chute 92 positioned in the block 61 by which the rivets are conducted to the rivet holding and driving means 25-24. In the event of any hesitancy on the part of the rivet to enter the chute 92, rivet discharge cams 93 formed by the opposite or upper sides or margins of the grooves 85 will engage the head of the rivet and in conjunction with the stripping finger 91 acting as a guide will move the rivet into the chute, through which it will move by gravity to the rivet holding and driving means 25-24.

Upon the movement of the rivet supporting member 64 to the right from the position shown in Fig. 8, or in the direction just described for moving the leading rivet into the chute 92, and in a direction to position the supporting member

64 as shown in Fig. 7, the high portions 82 of the gate operating cams 81 will be brought into position beneath the gate 72 and cause it to rise against the action of the springs 76, thereby moving the fingers 78 out of the path of the rivet heads on the supporting member and permit the weight of the rivets in the magazine 53 to move the next succeeding rivet into position against the surface 79 of the pawl 67 as illustrated in Fig. 7, after which the feeding operation just described is repeated to move the next leading rivet into the chute 92 when the rivet supporting member 64 is again moved toward the left from the position shown in Fig. 7, or toward the position shown in Fig. 8, to permit the then leading rivet to drop through the recesses 86 and into the chute 92 in the manner above described.

For actuating the rivet feeding means 26 by the main drive shaft 22 in properly timed relation with respect to the operation of the mattress border feeding rollers 37 and 38 and the rivet driving means 24, each of the rivet supporting members 64 is pivotally connected adjacent one of its ends with one end of a link 94 (Figs. 2 and 3), the opposite ends of the links being connected to a shaft 95 supported adjacent its ends in the upper free ends of a pair of arms 96 secured to a rock shaft 97 suitably supported on the frame 21, the opposite ends of the shaft 97 being provided with arms 98 having springs 99 connected thereto and to a portion of the main frame 21 for urging the shaft 97 and arms 96 in a clockwise direction (Fig. 3), and the rivet supporting member 64 toward the position shown in Figs. 6 and 7.

One of the arms 98 (Figs. 2 and 3) is connected to the lower end of a push rod 101 slidably mounted in a swinging support 102 pivotally mounted at 103 on a portion of the frame 21, the upper end of the rod 101 being provided with an anti-friction roller 104 adapted to be engaged by the cam 105 (Figs. 1 and 3) secured to the main shaft 22 in a manner to actuate the rod 101 to reciprocate the sliding rivet supporting members 64 in the manner above described for feeding rivets from the magazines 53 to the chutes 92.

Rivet holder and driving means

For driving rivets received from the rivet feeding means 26 through the mattress border A during the intervals between the movements thereof through the machine, a plurality or gang of driving members, each indicated as a whole, by the numeral 106, (Figs. 3, 7 and 14) are adjustably mounted in a vertically reciprocating head 107 slidably mounted in ways 108 (Figs. 1, 3 and 5) carried by the frame 21, each of the rivet driving members 106 comprising a shank portion 109 having a groove 111 formed therein adjacent one of its ends and adapted to receive one end of a stud 112 to prevent rotation of the shank 109, the head 107 being provided with a screw threaded plug 113 engageable with the upper end of the shank 109 for determining the position of the shank with respect to the head, in which position the shank portion 109 of the driving member may be secured by means of a set screw 114.

As clearly shown in Figs. 7 and 14, the shank portion 109 is provided with an elongated centrally disposed recess 115 and with oppositely disposed slots 116 extending through the walls of the recess and adapted to receive a cross pin 117, while the recess 115 is provided with a compression spring 118 adapted to operate between the

inner end of the recess 115 and a saddle member 119 mounted on a reduced portion 121 of the shaft 117 for urging the shaft, normally, into the lower end portion of the slots 116, the relationship of the saddle 119 with the reduced portion 121 of the shaft serving to retain the shaft against accidental displacement with respect to the shank portion 109 of the driving member.

It will be observed by reference to Figs. 3, 7 and 14 that the pin 117 extends a substantial distance beyond the opposite sides of the shank portion 109 and pivotally mounted on the projecting ends of the shaft are a pair of rivet holding elements 122 providing in effect a split housing indicated as a whole by the numeral 122a, clearly illustrated in Fig. 15, the elements 122 being of substantially U-shaped cross-section, and cooperating to form a chamber 123 adapted to slidably receive a plunger portion 124, screw threaded into the lower end of the shank portion 109 of the rivet driving member 106, the plunger 124 being provided adjacent its lower end with a reduced portion 125 adapted to enter a pocket

15 126 of correspondingly reduced dimensions adjacent and communicating with the chamber 123, the pocket 126 having a laterally extending inclined passage 127 associated therewith and adapted, in the raised position of the driving member and split housing 122a, to communicate with and form a continuation of the chute 92 for receiving rivets therefrom in a manner to conduct the rivets to the pocket 126 in position to be engaged by the reduced end portion 125 of

20 the plunger 124, the pivoted elements 122 being provided adjacent the lower end of the pocket 126 with inwardly extending cam portions 128 for supporting the head of the rivet thereon, as illustrated in Fig. 7, until engaged by the lower

25 end of the portion 125 to eject the rivet therefrom, through the material of the mattress border and into engagement with an anvil 129 mounted on the frame 21 beneath the mattress border for spreading and clinching the shank

30 portion of the rivet as illustrated in Fig. 14.

35 40 45 For actuating the head 107 in a manner to move the rivet driving member 106 and associated parts vertically, the head 107 is provided adjacent its upper side with a roller 131 adapted to engage an internal double faced cam 132 mounted on the shaft 22 in a manner to move the driving members in a vertical direction when the shaft 22 is rotated.

50 55 60 65 70 75 Adjustably mounted on the frame 21 are a pair of substantially parallel stop bars 133 against which the projecting ends of the pins 117 of the respective rivet driving members 106 will engage in their downward movement under the influence of the spring 118 and the shank portion 109 of the driving member, in a manner to arrest the movement of the pin and split housing elements 122, the movement of the shank portion 109 of the driving member being permitted to continue due to the yielding of the spring 118 and under the influence of the cam 132 in a manner to cause the reduced portion 125 of the plunger 124 to engage a rivet supported on the cam portions 128 of the elements 122 and to project the rivet therefrom as illustrated in Figs. 14 and 15, the spring 118 yielding to permit such relative movement of the shank portion 109 and the units 122, while the action of the stop bars 133 serves to position the pin 117 in the upper end portions of the slots 116 as shown in Fig. 14. During the ejecting of a rivet from the pocket 126 in the

manner above described, the lower end portions of the elements 122 are forced apart, as shown in Fig. 15, against the action of a resilient split ring 134 positioned preferably adjacent the upper ends of the elements 122 and tending normally to urge the elements toward each other.

For retaining the material of the mattress border A in relatively fixed position during the riveting operation, the presser foot 36 (Fig. 3) is moved downwardly by a pair of cams 135 (Figs. 1 and 3) mounted on the shaft 22 and engageable with rollers 136 carried adjacent the upper ends of a pair of rods 137 connected adjacent their lower ends with the presser foot 36, thereby holding the border material firmly against the guide 35, and while held in such position, the rivet driving member 106 is operated to project a rivet from the pocket 126 through the material of the border and into engagement with the anvil 129 for spreading or heading the shank portion of the rivet, as clearly illustrated in Fig. 14. The rods 137 are provided with springs 137a operating between guide brackets 21a on the frame 21 and a collar 137b on the rods 137 for moving the presser foot 36 to raised position.

For adjusting the stop bars 133 relatively to the movement of the head 107, the opposite ends of the bars may be secured to blocks 138 (Figs. 1, 3, 7 and 14), and adjusting screws 139 passing freely through the blocks 138 may be screw threaded into brackets 141 rigidly secured to the frame 21 and the adjusting screws 139 secured in desired position by means of set screws 142, as clearly shown in Figs. 1 and 3.

For counterbalancing the weight of the head 35 40 45 50 55 60 65 70 75 80 85 90 95 100 105 110 115 120 125 130 135 140 145 150 155 160 165 170 175 180 185 190 195 200 205 210 215 220 225 230 235 240 1. A mattress border riveting machine comprising a frame, a main drive shaft rotatably mounted therein, an anvil mounted in said frame, feeding means operatively connected to said drive shaft for feeding the material to be operated upon intermittently through the machine above said anvil, a rivet guide and holder comprising a plurality of hingedly connected yieldably separable members having a chamber formed therein and operatively related to said material, a rivet driving member slidably mounted in said chamber and operatively related to said anvil, said rivet driving member being operatively connected to said drive shaft in a manner to be actuated thereby for moving said guide and holder downwardly toward said material and driving rivets intermittently through said material during the interval between the movements thereof, an adjustable stop for limiting the downward movement of said guide and holder, a plurality of cam surfaces on said guide operatively related to said rivet driving member during the downward movement thereof for separating the lower end portions of said hingedly connected guide members to discharge a rivet therefrom, and intermittently operated rivet separating and feeding means actuated by said drive shaft, said separating means having an inclined chute associated therewith for directing rivets singly and by gravity to said guide and holder and into position therein to be engaged by said rivet driving member.
2. A mattress border riveting machine comprising a frame, a rivet magazine mounted thereon, a rivet supporting member mounted on said frame adjacent the discharge end of said magazine for receiving rivets successively therefrom, means for segregating a single rivet from the other rivets on said supporting member, a discharge chute having a receiving end adjacent said supporting member, and means associated with said member for permitting the escape of rivets from the supporting member to said chute.
3. A riveting machine comprising a frame, a rivet magazine mounted thereon, a supporting block mounted on said frame, a rivet supporting member movably mounted on said block adjacent the discharge end of said magazine for receiving rivets successively therefrom, means for segregating the leading rivet from the other rivets on said supporting member, a discharge chute having a receiving end adjacent said supporting member, and means associated with said member and adapted to be brought into operative relationship with said leading rivet by the movement of said member for permitting the escape of said leading rivet from the supporting member to said chute.
4. A riveting machine comprising a frame, a rivet magazine mounted thereon, a supporting block mounted on said frame, a pivot supporting member slidably mounted on said block adjacent the discharge end of said magazine for receiving rivets therefrom successively and in alignment with each other, a movable gate on said block for segregating the leading rivet from the other of said aligned rivets on said supporting member, a discharge chute having a receiving end adjacent said supporting member, and a recessed portion on said member adapted to be brought into operative relationship with said leading rivet by the movement of said member for permitting the escape of said leading rivet from the supporting member to said chute.
5. A riveting machine comprising a frame, a rivet magazine mounted thereon, a supporting block mounted on said frame, a rivet supporting member slidably mounted on said block adjacent the discharge end of said magazine for receiving rivets therefrom successively and in alignment with each other, said supporting member having bifurcations adjacent one of its ends for supporting the heads of said rivets and forming a slot between the bifurcations adjacent the central portion of the member for receiving the shank portions of the rivets, a vertically movable gate on said block for segregating the leading rivet from the other of said aligned rivets on said supporting member, means for retaining said leading rivet against movement horizontally relative to said gate, said bifurcations having downwardly extending grooves formed in their respective adjacent side portions and having recesses adjacent the upper ends of the respective grooves for receiving the head of said leading rivet when said recesses are brought into vertical alignment therewith by the movement of said rivet supporting member in one direction, a discharge chute in substantially the central longitudinal vertical plane of said slot and adapted for cooperative relationship with the lower end portions of the grooves formed in the respective bifurcations of said supporting member for receiving rivets therefrom, a stripper finger extending into said slot for guiding the rivets into said chute when the rivet supporting member is moved in the opposite direction, and rivet discharging cams on said bifurcations for moving said rivet into said chute during the movement of said supporting member in said opposite direction.
6. A riveting machine comprising a frame, a rivet magazine mounted thereon, a supporting block mounted on said frame, a rivet supporting member slidably mounted on said block adjacent the discharge end of said magazine for receiving rivets therefrom successively and in alignment with each other, said supporting member having bifurcations adjacent one of its ends for supporting the heads of said rivets and forming a slot between the bifurcations adjacent the central portion of the member for receiving the shank portions of said rivets, a vertically movable gate on said block for segregating the leading rivet from the other of said aligned rivets on said supporting member, yieldable means mounted on said block for retaining said leading rivet against movement horizontally relative to said gate, said bifurcations having downwardly extending grooves formed in their respective adjacent side portions and having recesses adjacent the upper ends of the respective grooves for receiving the head of said leading rivet when said recesses are brought into vertical alignment therewith by the movement of said rivet supporting member in one direction, means on said supporting member and block respectively for actuating said yieldable retaining means, a discharge chute in substantially the central longitudinal vertical plane of said slot and adapted for co-operative relationship with the lower end portions of the grooves formed in the respective bifurcations of said supporting member for receiving rivets therefrom, a stripper finger extending into said slot and forming a continuation of a portion of said chute for guiding the rivets into the chute when the rivet supporting member is moved in the opposite direction, and rivet discharging cams on said bifurcations for moving said rivet into said chute during the movement of said supporting member in said opposite direction.

7. A riveting machine comprising a frame, a rivet magazine mounted thereon, a supporting block mounted on said frame, a rivet supporting member slidably mounted on said block adjacent the discharge end of said magazine for receiving rivets therefrom successively and in alignment with each other, said supporting member having bifurcations adjacent one of its ends for supporting the heads of said rivets and forming a slot 5 between the bifurcations adjacent the central portion of the member for receiving the shank portions of said rivets, a vertically movable gate on said block for segregating the leading rivet from the other of said aligned rivets on said supporting member, resilient means operatively related to said gate and block and a cam on said supporting member for moving the gate into and out of operative engagement with the rivet heads on the supporting member, a yieldable pawl pivotally mounted on said block for retaining said leading rivet against movement horizontally relative to said gate, said bifurcations having downwardly extending grooves formed in their respective adjacent side portions and having recesses 10 adjacent the upper ends of the respective grooves for receiving the head of said leading rivet when said recesses are brought into vertical alignment therewith by the movement of said rivet supporting member in one direction, a second cam on said supporting member engageable with said pawl when the supporting member is moved in said one direction to remove the pawl from rivet retaining position, a discharge chute in substantially the central longitudinal vertical plane of said slot and adapted for co-operative relationship with the lower end portions of the grooves formed in the respective bifurcations of said supporting member for receiving rivets therefrom, a stripper finger extending into said slot for guiding the rivets into said chute when the rivet supporting member is moved in the opposite direction, and rivet discharging cams on said bifurcations for moving said rivet into said chute during the movement of said supporting member 15 in said opposite direction.

8. A riveting machine comprising a frame, a rivet magazine mounted thereon, a supporting block mounted on said frame, a rivet supporting member slidably mounted on said block adjacent the discharge end of said magazine for receiving rivets therefrom successively and in alignment with each other, said supporting member having bifurcations adjacent one of its ends for supporting the heads of said rivets and forming a slot 20 between the bifurcations adjacent the longitudinal central portion of the member for receiving the shank portions of said rivets, a vertically movable gate on said block for segregating the leading rivet from the other of said aligned rivets on said supporting member, means for retaining said leading rivet against movement horizontally relative to said gate, said bifurcations having downwardly extending grooves formed in their respective adjacent side portions and having recesses 25 adjacent the upper ends of the respective grooves for receiving the head of said leading rivet when said recesses are brought into vertical alignment therewith by the movement of said rivet supporting member in one direction, the lower side portion of the respective grooves providing rivet guides below said recesses, a discharge chute in substantially the central longitudinal vertical plane of said slot and adapted for co-operative relationship with the lower end portions 30 of the grooves formed in the respective bifurca-

tions of said supporting member for receiving rivets therefrom, and a stripper finger extending into said slot for stripping rivets from said guides and directing the rivets into said chute when the rivet supporting member is moved in the opposite direction, the upper side portions of the respective grooves providing rivet discharging cams on said bifurcations for moving said rivet into said chute during the movement of said supporting member in said opposite direction. 5

9. A riveting machine comprising a frame, a rivet magazine mounted thereon, rivet feeding means adjacent the discharge end of said magazine for receiving rivets successively therefrom, an inclined discharge chute having a receiving end adjacent said feeding means for receiving rivets singly therefrom, and rivet holding and driving means adjacent the discharge end of said chute, said holding and driving means comprising a vertically reciprocating driving member, a rivet holder comprising a pair of cooperable elements pivotally mounted on said driving member and relatively movable longitudinally with respect thereto, said holder having a chamber therein adapted to slidably receive said driving member and having a pocket provided with a laterally inclined passage adapted to communicate with the discharge end of said chute for conducting rivets therefrom to said pocket to be held therein in position to be engaged by said driving member, resilient means for urging said cooperable elements toward each other, and a pair of cam portions on the respective rivet holder elements operatively related to said driving member for swinging said elements about their pivotal connection therewith during the relative longitudinal movement thereof in a downward direction with respect to said rivet holder. 10

10. A riveting machine comprising a frame, a rivet magazine mounted thereon, rivet feeding means adjacent the discharge end of said magazine for receiving rivets successively therefrom, an inclined discharge chute having a receiving end adjacent said feeding means for receiving rivets singly therefrom, and rivet holding and driving means adjacent the discharge end of said chute, said holding and driving means comprising a vertically reciprocating driving member, a rivet holder comprising a pair of cooperable elements pivotally mounted adjacent their upper ends on said driving member and movable therewith and relatively movable longitudinally with respect thereto, a stop for arresting the downward movement of the holder, said holder having a chamber therein adapted to slidably receive said driving member during the relatively longitudinal movement of the driver and holder, said holder having a pocket provided with a laterally inclined passage adapted to communicate with the discharge end of said chute for conducting rivets therefrom to said pocket to be held therein in position to be engaged by said driving member in its downward movement relatively to said holder, resilient means for urging said cooperable elements toward each other, and a pair of cam portions on the respective rivet holder elements adjacent their lower ends adapted to be engaged by a rivet head for swinging said elements about their pivotal connection with said driving member under the influence thereof during the relative longitudinal movement of the driving member with respect to said rivet holder for projecting a rivet from said pocket. 15

11. A riveting machine comprising a frame, a drive shaft and a plurality of rivet magazines 20

- mounted thereon, a supporting block mounted on said frame, a plurality of reciprocating rivet supporting members operatively connected to said shaft and slidably mounted on said block adjacent the discharge ends of the respective magazines for receiving rivets successively therefrom, a plurality of gates operatively related to said supporting members for segregating a single rivet from the other rivets on each of the respective 5 supporting members, a plurality of discharge chutes mounted in said block and having receiving ends adjacent the respective rivet supporting members, means associated with said rivet supporting members for permitting the escape of rivets therefrom to said chutes, a vertically reciprocating head slidably mounted on said frame and operatively connected to said drive shaft, and a plurality of transversely aligned rivet holding and driving means adjacent the discharge ends 10 of said chutes, each of said holding and driving means comprising a driving member rigidly secured to said head, a rivet holder mounted on said driving member for movement therewith and relatively movable longitudinally with respect thereto, said holder having a chamber therein adapted to slidably receive said driving member and having a pocket adapted to communicate with one of said chutes for receiving rivets therefrom and to hold said rivets in position to be engaged by said driving member. 15
12. A riveting machine comprising a frame, a drive shaft and rivet feeding means mounted on said frame, rivet holding and driving means on said frame operatively related to said feeding means, said rivet holding and driving means comprising a vertically reciprocating head on said frame operatively connected to said driving shaft, a rivet driving member adjustably mounted in said head, a rivet holder connected to said member and movable therewith and relatively thereto, said holder having a pocket therein operatively related to said feeding means for receiving rivets therefrom, and a stop adjustably mounted on said frame for arresting the downward movement of said holder under the influence of the downward movement of said driving member, the connection between said rivet driving member and holder including a slot and resilient member for permitting continued movement of said driving member to eject a rivet from said holder after the movement of the holder has been arrested by said stop. 20
13. A riveting machine comprising a frame, a drive shaft and rivet feeding means mounted on said frame, rivet holding and driving means on said frame operatively related to said feeding means, said rivet holding and driving means comprising a vertically reciprocating head on said 25 frame operatively connected to said drive shaft, a rivet driving member having an elongated recess and transversely disposed slots formed therein, a pin extending transversely through said slots and recess, a rivet holder mounted on said pin and having an elongated chamber adapted to receive said driving member, said holder having an elongated chamber adapted to receive said driving member, said holder having a pocket therein operatively related to said feeding means for receiving rivets therefrom in position to be engaged by said driving member, a stop adjustably mounted on said frame and engageable by said pin for arresting the downward movement of said holder under the influence of the downward movement of said driving member, and a resilient means in said recess and operatively related to said pin for permitting the continued movement of said driving member to eject a rivet from said pocket after the movement of the holder has been arrested by said stop. 30
14. A riveting machine comprising a frame, a drive shaft and a plurality of rivet feeding means operatively related thereto mounted on said frame, a vertically reciprocating head on said frame operatively connected to said drive shaft, counterbalancing means operatively related to said head and frame, a plurality of rivet holding and driving means on said head operatively related to the respective feeding means, each of said rivet holding and driving means comprising a rivet driving member having an elongated centrally disposed recess and transversely disposed elongated slots formed therein, a pivot pin extending transversely through said slots and recess, a rivet holder comprising a pair of cooperable elements pivotally mounted adjacent their upper ends on said pin and cooperating to form an elongated chamber in said holder adapted to slidably receive said driving member, resilient means for urging said elements toward each other, said holder having a pocket therein operatively related to one of said feeding means for receiving rivets therefrom in position to be engaged by said driving member, a pair of stop bars adjustably mounted on said frame and engageable by said pin for arresting the downward movement of said holder under the influence of the downward movement of said driving member, and a spring in said recess and operatively related to said pin for permitting the continued movement of said driving member to separate the lower ends of said element against the action of said resilient means and eject a rivet from said pocket after the movement of the holder is arrested by said stop bars. 35

SAM MARSACK.
WILLIAM LOEFFLER, JR.

CERTIFICATE OF CORRECTION.

Patent No. 2,172,446.

September 12, 1939.

SAM MARSACK, ET AL.

It is hereby certified that error appears in the printed specification of the above numbered patent requiring correction as follows: Page 5, first column, line 61, claim 4, for the word "pivot" read rivet; and that the said Letters Patent should be read with this correction therein that the same may conform to the record of the case in the Patent Office.

Signed and sealed this 31st day of October, A. D. 1939.

Henry Van Arsdale,

(Seal)

Acting Commissioner of Patents.
